UNITED STATES PATENT OFFICE.

KENTON C. KUNKLE, OF BELLEVUE, KENTUCKY, ASSIGNOR OF ONE-HALF TO FRED G. KRUEGER, OF NORWOOD, OHIO.

JEWELER'S BLOWPIPE.

1,262,213.

Specification of Letters Patent. Patented Apr. 9, 1918.

Application filed December 17, 1917. Serial No. 207,409.

To all whom it may concern:

Be it known that I, KENTON C. KUNKLE, a citizen of the United States, and a resident of Bellevue, in the county of Campbell and State of Kentucky, have invented 5 certain new and useful Improvements in Jewelers' Blowpipes, of which the following is a full, clear, and exact description, reference being had to the accompanying 10 drawing forming part of this specification.

My invention relates to blow pipes particularly for jewelers' use, to take the place of the mouth pipes now used as blow pipes in most instances.

15 I am aware that there are in the art various instances where a source of supply of compressed air, a hand air bulb, or the like has been attempted to be employed in the place of the mouth pipe, but I do not know 20 of any instance where the necessary delicacies of adjustment of direction and density of flame have been accomplished sufficiently by these devices to replace the mouth pipe for even ordinary work.

25 It is the object of my invention to provide a mechanical blow pipe, in connection with a jeweler's burner which will accomplish most of the functions of the mouth blow pipe, in a simple manner to which a 30 workman can readily accommodate himself. Among other things I have found it requisite to a mechanical device for the above purpose to provide a fairly long air pipe, or blow pipe, which can be longitudinally 35 adjusted with relation to the burner, and which has at its end a substantially short and angling nozzle. In this manner I am enabled to get drafts of air through the pipe at all angles from directly across the 40 burner to parallel with the escape of gas therefrom, and still have the nozzle of the blow pipe closely adjacent the base of the flame, whereas were the nozzle long as compared to the blow pipe, the mouth of the 45 nozzle could not be maintained at the base of the flame for upward as well as cross-wise drafts.

50 It is my object to make the structure of the device as simple and elementary as possible, because a complexity of movements of a mechanical blow pipe makes it of little value in shop practice. I also desire to provide an assembly of gas pipe and blow

pipe, together with a slanting jeweler's burner, which is strong and compact and 55 can be sold as a unit for jewelers' use.

The above object and other advantages to be noted I accomplish by that certain construction and arrangement of parts to be hereinafter more specifically pointed out 60 and claimed.

In the drawing,

Figure 1 is a side elevation of the device.

Fig. 2 is a longitudinal section taken through the extensible blow pipe, the nozzle 65 being in elevation.

Fig. 3 is a detail side elevation of the bent up end of the air pipe on which the blow pipe is mounted.

Although my blow pipe device might be 70 employed in many ways in combination with a gas burner of jewelers' type, I have shown it only in relation to a special arrangement of gas pipe and burner which goes to make up a unit installation for jewelers' practice.

In the assembly selected for purposes of illustration of the invention, there is a gas pipe 1, and an air pipe 2, with valves 3 and 4 for the said two pipes respectively. The 80 gas pipe extends beyond the valve and is turned at an angle upwardly at 5, where it is fitted with the flat topped jewelers' burner 6. The burner 6, which is of any usual type is thus set at an angle to the 85 vertical.

The air pipe beyond the valve is turned up at 7, at a less angle than the gas burner pipe, the part 7 serving to telescope within the blow pipe. The blow pipe is in two 90 parts, as shown, a tube 8 having a finger piece 9 at the base thereof, and a telescoping tube 10 having the nozzle 11 at the end.

It should be noted that the nozzle is a short pipe of much smaller tubing, which is 95 extended at an angle to the axis of the tube 10. When the tube 8 is placed over the end of the air pipe at 7 and the tube 10 inserted in the tube 8, it can be seen that an extensible air pipe is provided. The angle of 100 the air pipe and the angle of the nozzle to the axis of the blow pipe made up by said telescoping tubes are such as to bring the nozzle into a position where the revolving of the tube on the end of the air pipe will 105 swing the nozzle through exactly the desired

arc. This arc should be such as to allow a jet of air directly across the base of the flame of the burner, and a jet directly parallel with the escaping gas or flames from the burner, together with the intermediate positions between said two extremes.

The extensibility or longitudinal adjustment of the blow pipe should be such as to permit its end to extend say to a position 10 over the center of the burner. The above adjustments of the nozzle and blow pipe need not be precisely as mentioned, as a substantial compliance with the above noted requisites would approximate by so much 15 the results gained by my invention.

In connection with the gas and air pipes, some sort of clamp is preferably provided as at 12 (Fig. 1), which will hold the two pipes together and make of the gas burner 20 and blow pipe a unit for sale to jewelers. A pilot light 13 will also be provided with the set.

The essential of the invention, as I see it at this time, is in the blow pipe having longitudinal adjustment toward the burner and provided with a nozzle at an angle to the axis of the pipe and of relatively small size with relation to the pipe.

Having thus described my invention, 30 what I claim as new and desire to secure by Letters Patent, is:—

1. In combination with a jeweler's burner, an air pipe and a straight blow pipe connected thereto, means for slidably and 35 rotatably mounting said blow pipe on said air

pipe, and a short nozzle for said blow pipe, extending at an angle to the axis of the pipe.

2. In combination with a gas burner, a blow pipe having a source of supply of air, and means having fixed relation with the 40 gas burner for extendibly and rotatably mounting the blow pipe, said blow pipe having a short nozzle extending at an angle to the axis of the pipe.

3. The combination with a jeweler's 45 burner set at an angle to the horizontal, of a revoluble, extendible, straight blow pipe having a slanting axial position, and a short nozzle for said blow pipe extending at an angle to the axis of the said pipe, for the 50 purpose described.

4. In a device of the character described, the combination of an air pipe and a gas pipe secured to each other, a gas burner on the gas pipe, a tubular end for the air pipe, 55 a straight tubular blow pipe adapted to telescope over the end of the air pipe, and a nozzle on the end of the blow pipe, extending at an angle to the axis of the blow pipe.

5. In a device of the character described, 60 the combination of an air pipe and a gas pipe secured to each other, a gas burner set slantingly on the gas pipe, a tubular end for the air pipe extending slantingly therefrom, a straight tubular blow pipe adapted 65 to telescope over the end of the air pipe, and a nozzle on the end of the blow pipe, extending at an angle to the axis of the blow pipe.

KENTON C. KUNKLE.
